PLAYING CARD

Andrew M. Hemmert, 2007 S. 65 St., Philadelphia, Pa.,
and Charles L. Becker, Cherry Hill, N.J.; said Becker
assignor to said Hemmert

Filed Sept. 25, 1964, Ser. No. 81,871

Term of patent 7 years

(Cl. D34—13)

The figure is a plan view of a playing card showing our new design.

The face of the card is conventional.

The characteristic feature of our design resides in the combination on the back of the playing card of the ornamental border around the representation of the two faces of a coin, all as shown.

We claim:

The ornamental design for a playing card, as shown and described.
